UNITED STATES PATENT OFFICE

JOHN C. DAVIS, OF BOWLING GREEN, KENTUCKY

ABSORBENT CONTAINER

Application filed February 15, 1932. Serial No. 593,178.

This invention relates to an improvement in absorbent containers for glass receptacles and the like. It is well known that when a Coco Cola glass or any liquid receptacle, is placed upon the counter of a drug store, the moisture from the glass or the overflow of the liquid in the glass leaves a small puddle upon the counter which necessitates the continuous wiping of the counter to avoid damaging the sleeves of the customers. It is also known that when the glass is removed from the counter or tray in which it is served that the aforesaid overflow or moisture collected on the bottom of the glass may drip upon the customers' clothing.

In order to avoid this I have provided a container which will absorb the moisture or liquid from the glass and keep the counter and clothing comparatively dry. This container may be decorated by scallops or jagged edges and forms a convenient manner of advertising.

Because of the cheapness of the material used in this absorbent container and simplicity of construction, it will be possible to discard the container each time at a minimum cost.

Referring to the drawings:

Figure 1 is an elevation of the container in use.

Figure 2 is a sectional view of the same.

Figure 3 is a sectional view on line 3—3 of Figure 2.

Figure 4 is a blank of the container.

Figures 5 and 6 show modifications of the forms that may be used.

Referring to Figure 2, which shows a glass 10 located in the container 11. The container 11 may be made out of one piece, having a rim 12, a bottom 13 and a flap 14. The entire material is constructed of an absorbent material such as ordinary blotter paper and is provided on the outside with a glazed finish for decorative purposes and for retaining the moisture in the container.

The obvious reason for making the container out of absorbent paper and providing the outside with a glazed finish is to prevent the deterioration of the absorbent paper due to the absorption of the liquid.

With this construction it can be readily seen that the exterior glazed surface will act as a water retaining medium and insure the rigidity of the structure.

The flap 14 is provided to serve as wedge

so as to firmly secure the glass in the container. The manner of attaching the flap to the container will be described below.

A separate disc 15 which is made entirely of the absorbent material is adhesively attached to the bottom 13 to absorb any moisture already present.

Referring to Figures 5 and 6, the edge 12 may be decorated in any manner such as indicated by the scalloped edges 16 or the jagged edges 17.

The container is formed by first bending over the flap 14 and the bottom 13 of the blanks shown, and then folding the edge 12 as indicated by the dotted lines 18, and then rolled around until the edges overlap a little and then adhesively attaching the edges. The additional absorbent bottom 15, which is cut to fit flush with the edges of 11, is adhesively attached after the forming of the container.

Referring to Figures 4, 5 and 6, the absorbent material is scived away at 19, so as to leave only the glazed surface present, in order to ensure perfect adhesion.

Having thus fully described my invention, what I claim is:

1. An absorbent coaster for a glass comprising a cylindrical portion and a bottom, said bottom having secured thereto a flap portion adapted to be turned vertically in respect to said bottom so as to lie against the inner wall of said cylindrical portion and adapted to have cooperative relation with said glass.

2. An absorbent container for a glass comprising a blank, said blank having a marginal area and a bottom area, said bottom area having attached thereto an extending flap, said flap, when the marginal area is bent in cylindrical shape, being adapted to lie against the cylindrical wall and forms a securing wedge for the glass.

3. An absorbent container for a glass comprising a blank, said blank having a marginal area and a bottom area, said bottom area having attached thereto an extending flap, said flap, when the marginal area is bent in cylindrical shape, being adapted to lie against the cylindrical wall and forms a securing wedge for the glass, said bottom area having secured thereto an auxiliary glazed backing.

In testimony whereof I affix my signature.

JOHN C. DAVIS. 110
